UNITED STATES PATENT OFFICE.

EDWIN LUNDGREN, OF FREDERICK, MARYLAND, ASSIGNOR TO COMBUSTION ENGINEERING CORPORATION, OF NEW YORK, N. Y., A CORPORATION OF NEW YORK.

AUTOMATIC STOKER.

Application filed July 27, 1922. Serial No. 577,824

The present invention relates to furnaces of the type in which the fuel is fed progressively while in the course of combustion toward a discharge outlet through which the 5 refuse of the fuel is automatically discharged, and has for its object to provide a novel and improved furnace of this character.

The several features of the invention will be clearly understood from the following description and accompanying drawings, in which—

15 Figure 1 is a longitudinal sectional view, partly in elevation, of a portion of an underfeed furnace embodying the features of the invention in their preferred form, the section being shown as taken on the line 1-1 of Fig. 2;

Fig. 2 is a sectional plan view taken on the line 2—2 of Fig. 1; and

Fig. 3 is a sectional plan view taken on the line 3—3 of Fig. 1.

The furnace illustrated in the drawings is of a common underfeed type having an underfeed grate section 2, an overfeed grate section 4 at the rear of the underfeed section, and an ash pit 6 at the rear of the overfeed section. The underfeed section is made up of a plurality of downwardly and rearwardly inclined retorts which are spaced apart, and the outer walls of the outer retorts are spaced from the side walls of the furnace, with rows of tuyère blocks 7 spanning the margins of the adjacent walls of the retorts and the margins of the outer walls of the outer retorts and the side walls of the furnace. The fuel while in the course of combustion is fed over the rows of tuyère blocks and the overfeed section by means comprising an auxiliary feeding device 8.

The furnace is further provided with a wind box 10 for supplying air to said grate sections, which is provided with a bottom wall 12 and a front wall 14. Air under pressure is supplied to the wind box 10 through main air supply conduits 16 which extend through the bottom wall 12, and each is provided with a damper 17 for controlling the supply of air to the wind box. The front wall of the ash pit 6 is made up of a hollow tuyère structure 18 located directly beneath the lower end of the overfeed grate section 4, and with a hollow tuyère structure 20 located beneath the structure 18. The exposed walls of the hollow structures 18 and 20 are

provided with tuyère openings 22, and air is supplied to the interior of said structures from the main supply conduits 16. As shown in Fig. 2, each of the tuyère structures 18 and 20 is made in sections which are arranged in groups of three. Each group of sections of the tuyère structure 18 is in communication with an air chamber 23 through a conduit 24, and each group of sections of the tuyère structure 20 is in communication with the air chamber 23 through a conduit 26, the air chamber 23 being in communication with the main supply conduits 16 through branch conduits 28. The supplies of air to the tuyère structures 18 and 20 are independently controlled by dampers 30 and 32 mounted in the conduits 24 and 26, respectively, which are operable through suitable connections by means of vertically movable rods 34 and 36 at the front of the furnace. With this construction and arrangement it will be apparent that the air supplied to the ash pit may be varied as desired for different areas of the front wall of the ash pit and that this may be accomplished independently of the supply of air to the wind box, the supply of air to the wind box being also controllable.

The rear wall of the ash pit comprises tuyère blocks 38 of refractory material constituting the upper portion of the rear wall; a metallic tuyère structure 40 located directly beneath the tuyère blocks and having its exposed wall provided with tuyère openings 42; and a plate 44 located directly beneath the tuyère structure 40 constituting the lower portion of said rear wall of the ash pit. A space is provided back of the tuyère blocks 38 through which air is directed to the tuyère openings in the blocks, and air is supplied to the tuyère structure 40 through an air supply conduit 45. 85 90 95

The furnace illustrated in the drawings is also provided with a clinker crushing roll 46 arranged at the bottom of the ash pit and carried by a squared shaft 47 having its ends journaled in bearings on beams 48 arranged adjacent the side walls of the furnace. The clinker crushing roll is made up of sections that are arranged in groups of three corresponding to the group arrangement of the sections of the tuyère structures 18 and 20. The roll shaft 47 is mounted intermediate its ends in bearings arranged between the groups of sections of the clinker crushing 110

roll and mounted on beams 51 corresponding to the beams 48. The clinker crushing roll is rotated in a clockwise direction by means of a ratchet wheel 49 mounted on one end of the roll shaft 47 which extends through the side wall of the furnace. The ratchet wheel 49 is engaged by an actuating pawl 50 carried by an oscillating lever 52 which is actuated by suitable means through a link 54. 5 The clinker crushing roll 46 is provided with clinker crushing teeth 56 which cooperate with clinker crushing teeth 57 on the plate 44. The clinker crushing roll is mounted close to the lower end of the toothed plate 44 and is spaced a considerable distance back of the lower end of the lower tuyère structure 20. A dump grate 58 extends between the forward portion of the clinker crushing roll and the lower end of the forward wall 20 of the ash pit and its rear edge is provided with tooth like projections 59 that extend between the teeth of the roll. This dump grate is made in sections which are arranged in groups which correspond in arrangement 25 to the groups of sections of the tuyère structures 18 and 20 and the clinker crushing roll 46. Each group of sections of the dump grate is mounted on a shaft 60, the several shafts having their ends journaled in bearings on the beams 48 and 51. Each group of sections of the dump grate is adapted to be independently swung downwardly and returned to its normal refuse supporting position by means of an arm 64 having one end 30 secured to its shaft 60 and its other end connected by a link 66 with a depending arm of a bell crank 68, the other arm of the bell crank being provided with segmental gear teeth 70 that are engaged by a worm 72 carried by a shaft 74 which is adapted to be operated by a hand wheel 76 conveniently located at the front of the furnace. This sectional construction of the dump grate enables different parts of the contents of the 40 ash pit to be separately discharged. 45

The exposed wall of the tuyère structure 18 and the upper portion of the exposed wall of the tuyère structure 20 are inclined downwardly and rearwardly substantially 50 in a plane tangent to the forward portion of the periphery of the clinker crushing roll 46, and the lower portion of said wall of the structure 20 is inclined downwardly and forwardly to the forward portion of the dump grate 58. The lower portion of the rear wall of the ash pit comprising the metallic tuyère structure 40 and the plate 44 are inclined slightly downwardly and forwardly toward the clinker crushing roll. 55

With this construction it will be apparent that the rearwardly or inwardly inclined portions of the front wall of the ash pit and the inclined portion of the rear wall of the ash pit will cooperate to direct clinkers and 60 ashes down upon the clinker crushing roll, 65

while the lighter particles of the refuse will be permitted to drop back upon the dump grate until the spaces over the dump grate defined by the downwardly and forwardly inclined lower portion of the front wall of the ash pit and said plane which is tangent to the periphery of the roll, is filled, thus insuring proper operation of the roll on all of the heavier particles of the refuse. It will also be apparent that this construction and arrangement enables substantially all of the contents of the ash pit to be dumped out, upon the dump grate being swung down. 70 75

The arrangement of the metallic tuyère structure 40 reduces the liability of clinkers forming on the rear wall of the ash pit, and yet this structure is located a sufficient distance below the bed of burning fuel to be effectively protected from becoming overheated. 80 85

The metallic tuyère structure 40, and the clinker crushing plate 44 are each made up of sections which are arranged in groups corresponding to the sectional arrangement of the tuyère structures 18 and 20, clinker crushing roll 46, and dump grate 58. This sectional arrangement enables the width of the furnace to be easily extended. 90 95

As will be evident to those skilled in the art my invention permits of various modifications without departing from the spirit thereof or the scope of the appended claims. 95

What I claim is:

1. A furnace having, in combination, an underfeed grate section, an overfeed grate section, at the rear of the underfeed grate section, an ash pit at the rear of the overfeed grate section, a clinker crushing roll located adjacent the lower end of the rear wall of the ash pit, and a dump grate arranged in a substantially horizontal plane and extending between the clinker crushing roll and the forward wall of the ash pit. 100 105

2. A furnace having, in combination, an underfeed grate section, an overfeed grate section at the rear of the underfeed section, an ash pit at the rear of the overfeed section, a toothed clinker crushing roll located adjacent the lower end of the rear wall of the ash pit, means for rotating the roll in a direction to cause the ashes to be discharged between the roll and said rear wall, and a dump grate extending between the clinker crushing roll and the forward wall of the ash pit having projections extending between 110 115 the teeth of the clinker crushing roll. 120

3. A furnace having, in combination, an underfeed grate section, an overfeed grate section at the rear of the underfeed section, an ash pit at the rear of the overfeed section having the upper portion of its front wall inclined downwardly and rearwardly, and the lower portion thereof inclined downwardly and forwardly, a clinker crushing roll arranged adjacent the lower end of the 125 130

rear wall of the ash pit, and a dump grate extending between the clinker crushing roll and the lower end of said lower portion of the front wall of the ash pit.

- 5 4. A furnace having, in combination, an underfeed grate section, an overfeed grate section at the rear of the underfeed section, an ash pit at the rear of the overfeed section having the upper portion of its front wall 10 inclined downwardly and rearwardly, and the lower portion thereof inclined down-

wardly and forwardly, a clinker crushing roll arranged adjacent the lower end of the rear wall of the ash pit and having the forward portion of its peripheral surface arranged tangent to substantially the plane of said inclined upper portion of the front wall of the ash pit, and a dump grate extending between the clinker crushing roll and the lower end of the front wall of the ash pit. 15

EDWIN LUNDGREN.
